UNITED STATES PATENT OFFICE

HENRY PETERSEN, OF MOUNT AUBURN, IOWA

ROTARY FORCE PUMP

Application filed December 5, 1928. Serial No. 323,936.

My invention relates to certain new and useful improvements in rotary force pumps of that general type embodying an eccentrically mounted rotary element and pistons which, during the rotary movement of said element, are successively centrifugally brought into contact with the inner surface of walls of the cylinder within which they are located.

10 The present invention has for an object, among others, to improve upon prior constructions of this general character and to provide a simple, efficient, rotary pump of few parts, those arranged in small compass 15 and embracing a generic feature, a piston, with intersecting through passages upon one face, in which passages are disposed elements, such as rollers which are at all times so disposed as to have positive continued peripheral contact each with the adjacent roller or member. These rollers or members are so disposed that they have freedom of movement so as to reduce friction to a minimum, and as each outer roller in its turn is brought 25 into contact with the wall of the eccentric passageway, it is moved along in contact therewith throughout its course.

The piston body moves within its cylinder, but the piston shaft does not extend into the 30 chamber in which is provided the eccentric passageway or wall, thus leaving the case of the piston head such as to be provided with intersecting passageways for the movement of the rollers or other bodies, the intermediate 35 or center roller occupying the space generally occupied by the end of the piston shaft in prior devices of this character. This permits of my utilization of this space usually occupied by the end of the piston shaft to form 40 the intersecting passageway in the acting face of the piston body. These passages, or what may be termed "the roller carriers" intersect each other at right angles, extending 45 to the periphery of the piston body on a plane with the floor of the eccentric for free roller movement, the said passages being of the same depth as the rollers or members that move therein. This not only simplifies the structure, but permits me to use the arrangement 50 of the rollers or bodies herein disclosed

so that they shall have, at all times, direct intimate contact with each other under all conditions. The floor of the passageway and the floor of the eccentric are perfectly smooth and in alignment with each other.

The invention has for an object, among others, to provide a device of this general character which shall be strong and durable, simple in its construction, composed of comparatively few parts and those not liable to get out of order, but quickly and cheaply replaced when necessary, and a resulting structure which is capable of long continuous use without wear or necessity of attention.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which

Fig. 1 is a top plan of my improved pump with a part broken away and portions shown in section.

Fig. 2 is a section on the line 2-2 of Fig. 3.

Fig. 3 is a section on the line 3-3 of Fig. 1.

Fig. 4 is an end view of the body member 80 with the piston therein.

Fig. 5 is a similar view showing a modified form of inter-communicating passages and arrangement of contacting members.

Fig. 6 is a similar view showing another modified arrangement.

Like numerals of reference indicate like parts throughout the several views.

Attention is called to the fact that in all of the forms shown the generic feature of continuous direct intimate contact between the rollers or elements is maintained. By this means, positive uniform movement of the parts is at all times assured to the end that the action shall be continuous, uniform and at all times dependable.

The rollers or members which are movable in the grooves or passageways of the head of the piston may be solid or may be tubular or ring-formed, as may be found most expedi-

ent, the resultant action being in all cases the same.

In all the forms the movable elements have a rolling shift, the peripheries of the outermost ones having actual contact with the wall of the concentric path within which they travel, and the center roller or element has free movement to roll and shift as the piston shaft is cut smooth with the floor of the piston rack that carries the rolling members.

Referring to the drawings, Figs. 1, 2 and 3, 1 indicates the outer cylinder or casing of the device: 2 and 3 designate the inlet and outlet passages, it being understood that either 15 one may be the inlet and the other the outlet; that is, the device is arranged so as to operate either way.

This body or cylinder 1 is provided with the tubular extension 4 to support the piston shaft, the outer end of which shaft is designed to receive a drive pulley 5. This extension 4 may be fixed in position in any suitable manner; in the present instance shown as supported in a saddle 6, having openings 7 25 for the reception of bolts or other means by which it may be secured in the desired position. A strap or like member 8, or a staple bolt or the like, may be employed to firmly fix the member 4 within the saddle to prevent 30 relative movement of the member 4; any suitable means for holding the member 4 and other parts in place may be employed. The cylinder or casing 1 is formed with a concentric chamber 9 in which is mounted to revolve 35 a piston 10, the piston shaft 11 of which is disposed within the tubular extension 4, and thus the piston 10 revolves within the chamber 9, concentrically thereof. Beyond this chamber 9 the cylinder 1 is formed with an 40 eccentric chamber 12, the inner wall 13 of which is contacted by the piston members 14, the number of which may vary as herein illustrated.

These members 14 are arranged in grooves 45 or channels 15 in the piston head 10. In the form shown in Figs. 1 and 3, these channels 15 are arranged in the form of a cross at right angles, that is, the channels extending from side to side in one direction are at right angles 50 to those extending in the other direction, intersecting at the center, and the center is naturally substantially in alignment with the piston shaft 11. These channels form intermediate members 16, as clearly seen in Fig. 3, between each two of which, one of the members 14 is disposed.

In the operation of the device, the outermost rollers 14 are at all times in contact with the wall of the eccentric passage in the member 1, while the innermost one, in this instance, the center one, is at all times, in direct contact with the adjacent periphery of each of the other members, as clearly understood 65 from Fig. 3. Hence, there is no lost motion,

but the action must be continuous and dependable.

Referring to Fig. 5, the casing or member 1 is in all respects, substantially the same as shown in Figs. 1-4, except that in lieu of the body portion of the piston being constructed to accommodate five rollers or like members, the body or face of the piston is provided with passages 17, related as shown and intersecting each other at the center. In these 70 passageways are mounted for movement the members 18, four in number. These members may be solid as are those shown in Figs. 1-4, or they may be in the nature of tubes or rings as shown in Fig. 5, the said members 18 being disposed so that they are, at all times, in intimate rolling engagement with each other. In operation, the effect is the same; the members 18 having rolling contact with the vertical wall of the eccentric chamber of 75 the piston head or body.

In Fig. 6 I have chosen to show another form in which the body or head of the piston is provided with a single diametrically disposed passage 19 in which are disposed members 20 which may be solid or not as preferred, and these are so disposed as to have three rolling engagements with each other, the outermost of the members 20 being movable in contact with the wall of the eccentric passageway in which they travel. It will also be noted that these outer rollers or members 20 are also at all times in direct peripheral engagement with the intermediate roller as will be evident from Fig. 6.

It will be understood, of course, that the extension of the member 1 in the form shown in Figs. 4, 5 and 6, receives the shaft of the piston and that the latter is designed to be equipped with a pulley, the parts being securely fixed in proper position in any suitable manner.

As the operation in all the forms is for all intents and purposes the same, the description of one will suffice for all. Therefore, referring to Fig. 3, supposing the power is applied to the pulley 5 and the pump started into service. The liquid or air admitted through the passage 3 enters the chamber 21 which communicates with the eccentric face 22. The piston revolving in the direction of the arrow in Fig. 3, the liquid or air follows such course, being prevented from movement in the opposite direction by the frictional contact of the members 14 and the adjacent portion 16 of the piston head, and the liquid or air is carried along in the direction of the arrow (Fig. 3) and is confined against exit until the member 15, shown in the position in Fig. 3, passes the point 23, indicated in Fig. 3 when the liquid or air is free to escape through the outlet 2. This operation is continuous. The succeeding members 14 and 16 operate in the manner above described so long as the pump is running. One of the 100

members 14 at all times is in position to prevent back-flow of liquid or air. It will be noted that the members 14, have, at all times, direct peripheral rolling contact with the eccentric wall and with each other. The portions 16 of the piston head, however, do not always have contact with this eccentric wall. As seen in Fig. 3, the diametrically disposed portions 16 are alternately in contact with or 10 out of contact with this peripheral wall. Fig. 3 shows the two portions 16 at the top of the figure in close contact with the adjacent portion of the eccentric wall, and the intermediate portion 14 is also in contact with such 15 wall, so that exit of the liquid or air at such point is effectually prevented. When these parts are in this position, the other portions 16 are out of contact and somewhat removed from the adjacent portion of such eccentric 20 wall, as seen in the lower portion of Fig. 3.

When in this position, there is no escape of air or liquid in either direction at the points seen in the upper part of Fig. 3. This condition of things is always gradually 25 changing as the piston revolves. The next succeeding members 14 and 16 are brought into the position previously assumed by the parts, so that the condition seen in Fig. 3 is practically at all times the same, and the 30 liquid or air is conducted in a continuous stream through the outlet tube.

The same result is obtained with the form shown in Figs. 5 and 6. The portions 24 of the piston head serve the same way, at one 35 time closing the passage against escape of liquid or air, and each successive change brings about the same result.

In the form shown in Fig. 6, the operation is substantially the same. As seen in this 40 view, the portions 25 of the piston head or body are shown at the upper portion of the figure as serving to close the exit, at whatever portion, being removed out of contact with the wall of the eccentric portion, and these 45 parts constantly changing relative positions as long as the pump is operating. In this form, as well as the others, the rollers or member 20 are at all times in positive, frictional contact with each other, and the outer- 50 most ones always in rolling shifting engagement with the eccentric wall.

Modifications in detail may be resorted to without departing from the spirit of the invention or sacrificing any of its advantages. 55

What is claimed as new is:—

1. A rotary pump comprising a casing, a piston chamber therein, an eccentric chamber, a piston rotatable in the piston chamber, said 60 chamber having an unobstructed through passage extended transversely thereof, and members carried by the piston and each having shifting rolling contact with another and with the wall of the eccentric chamber, said 65 piston having portions intermediate said roll-

ing members for intermittent contact with the wall of the eccentric chamber.

2. A rotary pump embodying a casing with concentric portion and an eccentric chamber, a piston in the chamber having intersecting 70 unobstructed through passageways extended transversely thereof, and members occupying said passageways and disposed for continual shifting rolling contact each with another and with the wall of the eccentric 75 chamber.

3. A rotary pump embodying a casing having intake and discharge ports therein, a concentric portion and an eccentric chamber, a piston in the chamber having intersecting 80 unobstructed through passageways and members occupying said passageways and disposed for continual shifting rolling contact each with another and with the wall of the eccentric chamber, the piston having 85 portions serving as cut offs for said ports.

4. A rotary pump embodying a casing with concentric portion and an eccentric chamber, a piston in the chamber having through unobstructed intersecting passage- 90 ways and members occupying said passageways and disposed for continual shifting rolling contact each with another and with the wall of the eccentric chamber, the piston having 95 portions serving as cut offs for said ports, with adjacent walls of which the rolling members have continued engagement.

5. In a rotary pump having a passageway therein, extended transversely therethrough, unobstructed throughout its length, revolute 100 members in said passageway, said revolute members having at all times direct intimate rolling contact each with another and with the opposed walls of said passageway.

6. A rotary pump comprising a casing hav- 105 ing a concentric chamber therein and an eccentric chamber, a piston rotatable in said chambers and having intersecting passages extending transversely unobstructedly therethrough, outer members and an intermediary 110 member carried in said intersecting passages, the outer members having shifting rolling contact with said intermediary member and with the wall of the eccentric chamber.

7. A rotary pump comprising a casing hav- 115 ing a concentric chamber therein and an eccentric chamber, and a piston rotatable in said chambers and having a passage extending transversely therethrough, outer members and an intermediary member movable in the said passage, the outer members having shifting rolling contact with said intermediary member and with the wall of the eccentric chamber. 120

8. A pump comprising a cylinder formed 125 with a concentric chamber, a piston revolute within said cylinder, concentric thereof, members disposed in said eccentric chamber and contacting with the inner wall thereof, said piston having intersecting transverse 130

through passages unobstructed from end to end, and rolling members disposed in said passages at all times in direct contact with the wall of said eccentric chamber and each 5 with the adjacent periphery of another.

In testimony whereof I affix my signature.
HENRY PETERSEN.
